ABSTRACT

An input crankshaft is rotated causing an attached offset pin to engage a yoke arm. The yoke arm is connected in two spring links which, when the yoke arm is rotated, pivot in opposite directions causing the ends of an attached spring to be extended in opposite directions. Once rotation of the yoke arm passes a neutral point, and the links have extended the spring to its maximum extension, the contracting force of the spring then acts on the two spring links to rotate the yoke arm rapidly in the same direction as the input rotation in a quick snapping fashion. When the yoke arm rotates rapidly, a pin on the yoke plate engages an output drive lever which is connected by appropriate linkage to an operating shaft. The rapid snapping of the yoke arm which imparts motion to the output drive lever and the operating shaft, causes an electrical switch to open to break an electrical circuit or, upon reverse operation, to quickly close to make an electrical circuit.

HIGH VOLTAGE SWITCH OPERATING MECHANISM

BACKGROUND OF THE INVENTION

1. Field of the Invention

The present invention relates to high voltage electrical switches and more particularly to operating mechanisms for high voltage electrical switches which operate to cause a switch to quickly make and quickly break a circuit.

2. Description of the Prior Art

High voltage electrical switches are well known to the art. For example, an electrical switch of the quick-make, quick-break type are disclosed in U.S. Pat. No. 2,989,603 — Mikos et al., assigned to the assignee of this application. The Mikos et al. patent discloses and discusses rapid action switch operating mechanisms for operating interrupter switches.

The quick-make, quick-break switch often consists of an operating lever and a spring arrangement for causing the rapid action of an operating lever. Springs are often used in high voltage switch operating mechanisms because of the large amount of force generated by springs, and because such springs have essentially no reaction time delay once released.

The input to quick-make, quick-break switches is often provided by a lever which can be, but need not be, operated by hand. The output of quick-make, quick-break switches may be a switch blade or other switch contact mechanism. Thus, the principal use of such inventions is for manual operation in making or breaking a circuit under conditions of high voltage or excessively high currents, e.g., a fault current.

The use of springs in quick-make, quick-break electrical switches is well known in the art. However, such arrangements have typically only involved the expansion or contraction of the spring in one direction, and such single acting spring mechanisms have not in all instances completely solved the problems arising from opening and closing of high voltage circuits. When such circuits are interrupted by a low speed mechanism, arcing and high current flow and consequent danger to property and operating personnel can occur.

In addition, the absence of appropriate latching mechanisms for locking the switch in an open position can result in high current flow at in appropriate times exposing operating personnel to safety risks. Typically, prior art quick-make, quick-break switches have relied upon the position of the input lever to hold the switch in the open position once that position has been achieved. Some prior art, such as U.S. Pat. No. 2,939,603 — Mikos et al., discloses special constructions designed to prevent accidental closing of the switch contacts once they have been opened. Such constructions are obviously important to prevent the flow of electric current during repair of the equipment, but none of the above constructions disclose latch arrangements which can be unlocked from a remote position. Further, it would be advantageous to provide an arrangement that locks the switch in a closed position so that external forces or electromagnetic forces due to fault currents cannot accidentally open the switch.

Consequently, it would be a highly desirable advance in the art to provide a quick-make, quick-break switch for high voltage circuits which could be hand operated, and which could produce a rapid snapping opening ac-

tion of an electrical switch utilizing a double acting spring arrangement to produce maximum efficiency.

In addition, it would also be desirable to provide a means for holding the electrical switch in its open position, while allowing remote disengagement of this holding mechanism.

Further, it would be desirable to provide a means for closing an electrical switch with a rapid snapping action to reduce arcing.

10

BRIEF SUMMARY OF THE INVENTION

In accordance with the present invention, a high voltage switch operating mechanism comprises operating switch contacts connected to an operating means 15 which extends into a switch housing. Mounted within the housing and operably connected to the output means is an output drive lever. The output drive lever is free to rotate and has engaging abutments thereon which engage a pin projection on a yoke arm means.

20 An input crankshaft means mounted for rotation has an engaging pin which is positioned to engage an engaging surface on the yoke arm means.

The yoke arm means has first and second spring link means pivotably connected to its periphery. The spring link means are connected to wing arm means which are pivotably mounted so that rotation of the yoke arm means causes the wing arm means to separate, thus extending a spring connected between the wing arm means. When the rotation of the yoke arm means 25 reaches a point where the spring link means have caused the wing arm means to expand the spring to its maximum extension, further rotation of the yoke arm means results in the spring contracting to cause the spring link means to drive the yoke arm means rapidly in a snapping rotation. This motion continues until the spring reaches its normal, contracted position.

30 The rapid snapping rotation causes the pin projection on the yoke arm means to engage the engaging abutment on the output drive lever, thereby causing the drive lever to rotate rapidly to cause the output means to rapidly open the switch contacts.

35 Reverse rotation of the input crankshaft means in an opposite direction causes the elements described above to move in an opposite direction so that the switch contacts are rapidly closed in the same manner.

The present invention also includes a locking means for locking the operating means after the switch contacts are opened so that the switch contacts are not accidentally closed by wind or other external forces. 40 Rotation of the input crankshaft means in the opposite direction unlocks the locking means so that the switch contacts can be closed.

45 The present invention also includes an over center toggle means for locking the operating means in the switch closed position so that the switch contacts can only be opened as a result of rotation of the input crankshaft means.

50 Thus, it is a primary objective of the present invention to provide a quick-make, quick-break switch operating mechanism having a double acting spring for efficiently utilizing the spring energy by coupling both ends of the spring into a drive system.

55 Another object of the present invention is to provide a quick-make, quick-break switch operating mechanism such that the switch is held open not only by spring means but also by a locking means when the switch is in the open position.

A further object of the present invention is to provide a quick-make, quick-break switch operating mechanism such that the operating mechanism is locked in a switch closed position so that the switch contacts can only be opened by operation of the input crankshaft.

BRIEF DESCRIPTION OF THE DRAWINGS

FIG. 1 is a top partially fragmentary view of a preferred embodiment of the present invention.

FIG. 2 is a front elevational view of the preferred embodiment illustrated in FIG. 1.

FIG. 3 is a cross-sectional view of the preferred embodiment of the present invention taken substantially along line 3-3 in FIG. 1.

FIG. 4 is a cross-sectional view taken substantially along line 4-4 in FIG. 1.

FIG. 5 is a cross-sectional view taken substantially along line 5-5 in FIG. 1.

FIG. 6 is a fragmentary view taken substantially along line 6-6 in FIG. 1 showing the output drive lever, latch dog, and output lever in the switch closed position.

FIG. 7 is a fragmentary view taken substantially along line 6-6 in FIG. 1 showing the output drive lever, latch dog, and output lever in the switch open position.

DETAILED DESCRIPTION OF THE PREFERRED EMBODIMENTS

With reference to FIGS. 1, 2, and 3, operating mechanism 10 comprises housing 12, including front wall 14, side walls 15, back wall 16 joined together by bolts 18.

With reference to FIG. 1, input crankshaft 20 extends through bearing housing 22 which comprises body 24, enclosed roller bearing 30 (shown in dotted lines). Bearing housing 22 is mounted to front wall 14 by bearing housing bolts 28. Input crankshaft 20 includes crank arm 31 which extends away from the central axis of crankshaft 20. Mounted at the end of crank arm 31 is engaging pin 32 which extends parallel to the center axis of crankshaft 20. Crankshaft 20 also includes a narrowed portion 34 which extends through back wall 16 so that crankshaft 20 can rotate.

Pivably mounted on the narrowed portion 34 of input crankshaft 20 is yoke arm 36. At the upper edge of yoke arm 36 is slot 38 (see FIG. 5) having engaging surfaces 40 and 41 at the ends thereof. Mounted to extensions 42 of yoke arm 36 by pin 44 are first spring link member 46 and second spring link member 48. The opposite ends of first and second spring link members 46 and 48 are connected to first wing arm 50 and second wing arm member 52 respectively by pins 54. First and second wing arms 50 and 52 are pivotably mounted by shafts 56 to the interior of switch housing 12 so that first and second wing arms 50 and 52 can freely pivot about shaft 56. A spring 58 is connected at each end to first and second wing arms 50 and 52 by pins 54.

Mounted on the opposite side of yoke arm 36 is pin projection 60 that is positioned at a distance radially disposed from the central axis of rotation of yoke arm 36 so that rotation of yoke arm 36 causes pin projection 60 to travel in a circular arc.

Also pivotably mounted upon the narrowed portion 34 of input crankshaft 20 is output drive lever 62. Output drive lever 62 (see FIGS. 6 and 7) also has a slot 64 formed therein for receiving pin projection 60 of yoke arm 36. Slot 64 forms two abutting surfaces 66 and 67 at the ends of slot 64 against which pin projec-

tion 60 can engage output drive lever 62. Also pivotably mounted to output drive lever 62 by pin 69 is latch dog member 68 which is biased by a spring 70 (shown in dotted lines in FIG. 6) so that latch dog member 68 tends to rotate in a counterclockwise direction until arm 70 of latch dog member 68 engages a flange 72 on output drive lever 62. Latch dog member 68 also comprises arm 74 which extends at an angle to arm 70.

Pivotably connected an extended portion 76 of output drive lever 62 by pin 78 is drive link 80. Drive link 80 has formed at one end thereof a finger 81 that is adapted to engage the arm 70 of latch dog member 68 when output drive lever 62 is in the position as shown in FIG. 6.

The opposite end of drive link 80 is connected by pin 84 to output arm 86. Output arm 86 is rigidly attached to output shaft 88 by set screws 90 (see FIG. 1). Output shaft 88 extends through back wall 16 and is rotatably mounted by bearing housing 92 which encloses roller bearing 94 (shown in dotted lines). Bearing housing 92 is mounted to back wall 16 by bolts 96. Thus, rotation of output arm 86 causes output shaft 88 to rotate within roller bearing 94. Also mounted on output shaft 88 outside of back wall 16 is operating arm 98 that can be connected by appropriate linkage (not shown) to the switch contacts of a high voltage switch so that rotation of operating arm 98 causes the switch contacts to either open or close depending upon the direction of rotation of operating arm 98.

Operation of the preferred embodiment may be described as follows. An appropriate input driving arrangement can be connected to the end of input crankshaft 20 that extends through bearing housing 22 so that rotational movement can be imparted to input crankshaft 20. Such an input driving arrangement may take the form of a crank arm, mechanical gear, or chain and sprocket arrangement. FIGS. 1 and 2 show the operating mechanism 10 in the switch closed position. To achieve a switch open condition, input crankshaft 20 is rotated in a counterclockwise direction so that the engaging pin 32 on the end of crank arm 31 of input crankshaft 20 engages engaging surface 40 of yoke arm 36 (see FIGS. 3 and 5). As input crankshaft 20 is rotated, engaging pin 32 causes yoke arm 36 to rotate in a counterclockwise direction, thus causing first and second spring link members 46 and 48 to cause first and second wing arms 50 and 52 respectively to pivot in opposite directions thus extending spring 58. Continued rotation of yoke arm 36 will cause continued expansion of spring 58 until spring 56 reaches its maximum expansion at the point where first and second spring link members have reached the position where pins 44 are shown in dotted lines and designated as 44' in FIG. 5, and pins 54 on first and second wing arms 50 and 52 are in the position shown in dotted lines and designated as 54' in FIG. 5. At that point, the center line of first and second spring link members 46 and 48 are in the position shown in the dotted lines designated 46' and 48' respectively. The center line 46' and 48' is aligned with the center line of input crankshaft 20 which is the center of rotation of yoke arm 36. Continued rotation of yoke arm 36 in a counterclockwise direction will result in spring 58 contracting rapidly to cause spring link members 46 and 48 to impart rapid rotational motion to yoke arm 36, until pins 44 on yoke arm 36 reach the position indicated by the dotted lines designated as 44'' in FIG. 5. In this position pins 54

55
60
65
60
65

have returned to their original position, spring 58 has contracted to its original configuration, and the center line of first and second spring link members 46 and 48 have reached the position designated by 46" and 48" respectively.

The rapid rotational motion imparted to yoke arm 36 after spring link members pass the neutral position designated by the dotted line 46' and 48', causes pin projection 60 on yoke arm 36 to engage abutting surface 66 on output drive lever 62 thereby causing output drive lever 62 to rotate very rapidly in a snapping type action. The rapid rotational motion imparted to output drive lever 62 causes output arm 86 (see FIGS. 6 and 7) to also rotate very rapidly to the position shown in FIG. 7 as a result of the connection of drive link 80. The rapid rotation of output arm 86 is transmitted through output shaft 88 to cause connected operating arm 98 to pivot very rapidly in the same direction. An insulating link (not shown) connected to output arm 98 is connected to an appropriate high voltage switch and causes the contacts of the high voltage switch to open very rapidly as a result of the snap action of operating arm 98.

To close the switch contacts, after the switch is opened, input crankshaft 20 is rotated in a clockwise direction, and the sequence described above is reversed. Engaging pin 32 engages the engaging surface 41 (as shown in FIG. 5) thus causing yoke arm 36 to rotate in a clockwise direction as seen in FIG. 5 until pins 44 are moved from the position designated 44" to the position designated 44'. Once again, continued rotation of yoke arm 36 in a clockwise direction results in spring 58 causing first and second spring link members to transmit rapid rotational motion to yoke arm 36 until it reaches the position illustrated by the solid lines in FIG. 5. This rapid rotational motion of yoke arm 36 causes pin projection 60 to engage abutting surface 67 on output drive lever 62, thus causing output drive lever 62 to rotate very rapidly from the position illustrated in FIG. 7 to the position illustrated in FIG. 6. This rapid rotational motion of output drive lever 62 causes output arm 86 connected by drive link 80 to pivot very rapidly to the position illustrated in FIG. 6 thereby imparting rapid rotational motion to output shaft 88 and to operating arm 98 to rapidly close the switch contacts of the connected high voltage switch.

A locking means is provided in the form of latch dog member 68. When in the switch closed position, latch dog member 68 is held in the position illustrated in FIG. 6 by finger projection 81 on the end of drive link 80. In this position, latch dog member 68 is pivoted until arm 74 contacts the flange 72 on output drive lever 62, and the end of arm 74 disengages pin projection 60. In this position, pin projection 60 is free to move through slot 64 to engage abutting surface 66.

However, when output drive lever 62 is pivoted to the switch open position as illustrated in FIG. 7, the finger projection 81 on the end of drive link 80 disengages the arm 70 of latch dog member 68 thus permitting the spring biasing of latch dog member 68 to pivot latch dog member 68 in a counterclockwise direction as illustrated in FIG. 7. When output drive lever 62 is rapidly pivoted as a result of the snap action of yoke arm 36, output drive lever 62 will rotate to the position shown in FIG. 7 but pin projection 60 on yoke arm 36 will stop in the position shown in FIG. 7 so that latch dog member 68 can pivot to the position where the end

of arm 74 engages the surface of pin projection 60 thereby trapping pin projection 60 between abutting surface 67 and the end of arm 74 (see FIG. 7). In this position, output drive lever 62 and output arm 86 connected by drive link 80 are locked in the position shown in FIG. 7 and consequently the switch contact connected to operating arm 98 cannot be accidentally closed as a result of rebounding or by external forces.

However, during the closing sequence, since pin projection 60 engages abutting surface 67 to cause closing motion to be imparted to output drive lever 62, latch dog member 68 does not interfere with the closing sequence as long as the force provided to cause the closing results from input rotational motion from input crankshaft 20.

An additional feature of the present invention is that the switch contacts are locked in a closed position as a result of the toggle action of drive link 80 and output drive lever 62. In FIG. 6, it can be seen that output drive lever 68 and drive link 80 are in a position when the switch contacts are closed so that the center line of pin 78 is beyond the center line between the center line of input crankshaft 20 and the center line of pin 84. Thus, if force is exerted to the high voltage switch to cause the switch contacts to open, this force will be transmitted through output arm 86 to cause output arm 86 to rotate in a counterclockwise direction as viewed in FIG. 6. However, such force will only tend to cause the finger projection 81 on the end of drive link 80 to press against arm 70 of latch dog member 68. Since arm 74 of latch dog member 68 is against flange 72 of input drive lever 62, drive link 80 and output drive lever 62 are toggled so that the switch contacts cannot open. Thus, the switch contacts can only be opened as a result of rotational motion being imparted to output drive lever 62.

The major advantage of the present invention is the use of the double acting spring 58. Since a spring force of several hundred pounds is involved, it is undesirable to connect one end of the spring to the housing so that the spring is a single acting spring. If the spring were attached to the housing, a large reaction force would be applied to the housing with an equally large side thrust on the output drive lever. By using a double acting spring, side thrust loads on the members is avoided due to the symmetry of the design, and the reaction couple on the wing arm produces relatively low forces. Consequently, heavily loaded bearings are avoided resulting in lower friction during operation.

It should be expressly understood that various modifications, changes, and variations in the structure of the above-identified preferred embodiment may be made without departing from the spirit and scope of the present invention as defined in the appended claims.

I claim:

1. A high voltage switch operating mechanism for opening and closing the contacts of a high voltage switch comprising:
a spring having two ends for storing energy upon extension and rapidly releasing stored energy upon contraction;
a spring extending means for extending both ends of said spring simultaneously in opposite directions to cause said spring to store energy and for permitting said spring to contract rapidly to release the stored energy when said spring is expanded to a predetermined amount of extension;

input means for causing said spring extending means to extend said spring;
output means coupled to said spring extending means for receiving the released stored energy of said spring and causing said switch contacts to open and close rapidly in response to receipt of the stored energy.

2. A high voltage switch operating mechanism, as claimed in claim 1, further comprising:

locking means for locking said output means after the contacts of the high voltage switch are open so that the contacts cannot be accidentally closed, said locking means unlocking said output means in response to operation of said input means to close the switch contacts.

3. A high voltage switch operating mechanism, as claimed in claim 1, further comprising:

over center toggle means for locking said output means in the switch closed position so that the switch contacts can only be opened as a result of operation of the input means.

4. A high voltage switch operating mechanism for opening and closing the contacts of a high voltage switch comprising:

a housing;
input crankshaft means mounted for rotation within said housing and extending through an opening in said housing, said input crankshaft means including an engaging pin mounted thereon;

yoke arm means mounted for rotation within said housing, said yoke arm means having an engaging surface for engaging said engaging pin on said input crankshaft means, and a pin projection extending in an opposite direction from said engaging surface;

first and second spring link means having first and second ends pivotably connected at their first ends to said yoke arm means;

first and second wing arm means having first and second ends, said first and second wing arm means being pivotably mounted within said housing at their first end adjacent opposite sides of said yoke arm means, and said first spring link means being pivotably connected at its second end to the second end of said first wing arm means and said second spring link means being pivotably connected at its second end to the second end of said second wing arm means;

spring bias means having first and second ends, said first end being connected to the second end of said first wing arm means, and said second end being connected to the second end of said second wing arm means, said spring bias means tending to urge said first and second wing arm means to pivot to-

ward one another;
output drive lever means pivotably mounted within said housing, said output drive lever means having engaging abutments thereon for engaging said pin projection on said yoke arm means;
output means operably connected to said output drive lever means, said output means for causing the switch contacts to open and close in response to rotation of said output drive lever means; whereby rotation of said input crankshaft causes said engaging pin to engage said engaging surface on said yoke arm means to cause said yoke arm means to rotate so that said first and second spring link means cause said first and second wing arm means to pivot to expand said spring bias means from both ends until said yoke arm means rotates to a position where said spring bias means is expanded to a maximum distance so that further rotation of said yoke arm means results in said spring bias means contracting rapidly to cause said spring link means to impart rapid rotational motion to said yoke arm means thereby causing said pin projection to engage said engaging abutment on said output drive lever so that said output drive lever rotates to cause said operably connected output means to rapidly open and close the contacts of the high voltage switch.

5. A high voltage switch operating mechanism, as claimed in claim 4, further comprising:

locking means for locking said operating means after the contacts of the high voltage switch are opened so that said contacts cannot be accidentally closed, said locking means unlocking said operating means in response to rotation of said input crankshaft means and said yoke arm means in the opposite direction to close the contacts.

6. A high voltage switch operating mechanism, as claimed in claim 5, wherein said locking means comprises:

a latch dog member pivotably mounted to said output drive lever means, said latch dog member being spring biased to rotate to engage said pin projection on said yoke arm when said output drive lever rotates to open the contacts so that said output drive lever cannot rotate in an opposite direction until said yoke arm means is rotated by said input crankshaft means.

7. A high voltage switch operating mechanism, as claimed in claim 4, further comprising:

over center toggle means for locking said operating means in the switch closed position so that the switch contacts can only be opened as a result of rotation of the input crankshaft means.
